UNITED STATES PATENT OFFICE.

LUDWIG SEGER, OF EDGEWATER, NEW JERSEY.

HINGE LOCK.

Application filed May 12, 1922. Serial No. 560,340.

To all whom it may concern:

Be it known that I, LUDWIG SEGER, a citizen of the Republic of Switzerland, residing at Edgewater, county of Bergen, and State of New Jersey, have invented certain new and useful Improvements in Hinge Locks, of which the following is a specification.

This invention relates to improvements in hinges and hinge locks, particularly of the character described in my co-pending application, Serial No. 472,841, filed May 26, 1921, intended for use with step ladders or the like, when these ladders are to be employed as straight wall ladders with their uprights locked in alignment.

It is the principal object of the invention to provide a hinge or hinges for this purpose connected with suitable sleeves or socket members adapted to be secured to the upper ends of the side bars of the ladder.

Another object of the invention is the provision of a suitable fastening means for locking the hasps of the hinge members to the ladder uprights when the ladder sections are in their extended position, in order to enable the use of the extended ladder from either side and positively avoiding the danger of accidental separation of the ladder parts under the weight of a person by the oscillation of the hinge hasps.

With these objects in view, the invention consists of certain novel features of construction, combination and arrangement of parts, as will be hereinafter more fully described and claimed.

In the accompanying drawings forming a material part of this disclosure:

Figure 1 is a perspective view of a step ladder equipped with a hinge device constructed according to the present invention.

Figure 2 shows the device in Figure 1 set up as a straight wall ladder.

Figure 3 shows a hinge constructed according to the present invention in top plan, side end and bottom plan views.

Figure 4 is an enlarged detail perspective view of a hinge constructed according to the present invention provided with a hasp lock.

Figure 5 is a fragmentary detail view of a modified form of hasp lock.

Figure 6 shows in top, side and bottom plan views a modified form of hinge construction.

Figure 7 illustrates one form of hinge construction, Figure 6, and

Figure 8 illustrates another form of said hinge construction.

Referring to the drawings, 10 represents the side bars, and 11 the steps or rungs of the lower section, and 12 the side bars, and 13 the steps or rungs of the upper section of a step or wall ladder.

Secured in any suitable well known manner to the upper end of each side bar 10 and 12 is a metallic sleeve, cap or socket 14 of a construction illustrated in detail in Figure 4. Each pair of sockets 14 to be attached to the ends of the side bars of a ladder at their meeting points on one side of the ladder comprises a body part made extremely light by providing open spaces 15 in its side, bottom and end walls.

At its inner bottom end edge, one of the sleeves 14 carries spaced ears 16 through 75 which a pintle 17 is passed, which is also passed through an ear 18 in the center of the inner bottom end edge of the adjoining sleeve 14 which engages in the space between ears 16 and cotter pins 19 are passed through 80 the ends of pintle 17. The opposite, inner upper or top end edges of the sleeves 14 are provided with projections or noses 20 separated by a depression 21 in the top part of sleeve 14. The inner upper end edge of the adjoining part 14 carries a central projection 22 through which a pintle 23 is passed which is also passed through perforated ears 24 and 25 at the inner end of a hasp member 26, one ear on each side of the projection 22, while lateral shoulders 27, formed on the outer face of member 26 near and adjoining to ears 24 and 25 are adapted to engage in the spaces 28 behind noses 20 when the hasp is in its locking position. Each of 90 the sleeves 14 is provided with a lower inner shoulder 29 supporting the upper step 11 of the step ladder.

A snap lock 30 of the form illustrated in Figure 4 is secured upon the top of one of 100 the sleeves 14 and when the hasp 26 is swung into its locking position its curved side flanges 31 and 32 will allow a passage of the member 26 and hold the same in said clasp against accidental displacement.

The outer end of the other sleeve 14 is provided on its inner face with a recess 33 into which the ends of the upper rung 13

fits. The hasp member 26, as shown in Figure 5 is provided with a longitudinal slot 34, through which a rotatable locking member 35 projects which is secured at its lower end on the top of sleeve 14.

When the device is to be used as a step ladder, a connecting bar 36 is provided which is pivoted at one end to the inner face of one of the side bars 12 and adapted to grip with its free hook shaped end over a pin 37 on the inner face of one of the side bars 10. A platform 38 is hooked at one end to one of the rungs 13 and rests with its other end, when the device is to be used as a step ladder, on the top step 11.

In the modified form of hinge illustrated in Figures 6, 7 and 8, the hinge members or sleeves 39, 40 are either formed as shown in Figure 7 or as shown in Figure 8.

20 In the form illustrated in Figure 7, the sleeves 39 and 40 are formed by metal bands having one end 41 overlapping the other end 42 at the sides, while the inner end edges of the sleeves thus formed are bevelled as 25 at 43 and 44.

In the form illustrated in Figure 8, the sleeves 39 and 40 are formed open on three sides with upper flanges 45 and lower flanges 46 overlapping the side edges of the side 30 bars of the ladder. The ends of the side plates are connected at one end by a plate 47 and the upper and lower edges are bevelled as at 48 and 49 respectively. The hasp member 26 and the hinge members are otherwise connected in a manner similar to that 35 described with respect to hinge members 14.

Having thus described my invention what I claim as new and desire to protect by Letters Patent of the United States is—

40 1. In a sectional combination step and extension ladder, hinged members, adapted to engage the meeting ends of the side bars of said ladder, and to be secured thereto, shoulders formed at one end of one of said 45 members for supporting the uppermost step of the step ladder, hinge locks combined with said members for locking the side bars of said ladder sections in their adjusted positions as an extension ladder, clamps for 50 holding said hinge locks in their locking position, a hooked bar pivotally secured to one of the side bars of one of the step ladder

sections and to engage a pin on the other section, and a platform adapted to be attached to the rungs of one section and to rest 55 on top of the uppermost step of the other section.

2. In a sectional combination step and extension ladder, hinged sleeve members, each provided with a plurality of openings and a recess on one side of one of the members at its lower end for engagement by a ladder rung, said sleeves adapted to engage the meeting ends of the side bars of said ladder, means for securing said sleeve members on said sections, shoulders formed at one end of one of said members for supporting the uppermost step of the step ladder, a hinge lock including a hasp combined with said sleeve members for locking the side bars of said ladder sections in their adjusted position as an extension ladder, a spring clamp having upstanding flanges for engaging and holding said hinge lock in its locking position, a means for connecting the step ladder sections, and a platform for providing a firm support at the top steps of the step ladder.

3. In a sectional combination step and extension ladder, rungs connecting the side bars of one of said sections, and steps connecting the side bars of the other section, sleeve members each having a plurality of openings adapted to be secured to the meeting ends of the side bars of said ladder sections and having bevelled upper and lower inner edges, hinges connecting the lower parts of said members, a hinge lock at the upper parts of said members including a hasp pivotally secured to one member and engaging the other member, spring clamps for locking said hasp in its locking position in engagement with the second member when the sections of said ladder are in their adjusted position as an extension ladder, means for connecting two of the side bars of said ladder in its position for use as a step ladder, and a platform adapted to be hung from the rungs of one ladder section and to engage the uppermost step of the other ladder section to present an enlarged foot support.

In testimony whereof I have affixed my signature.

LUDWIG SEGER.
